UNITED STATES PATENT OFFICE.

RAY L. STOKELY, OF FLORAL PARK, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

Application filed June 7, 1923. Serial No. 643,870.

This invention relates to telephone exchange systems, and more particularly to such systems employing machine switching equipment.

5 In a copending application, Serial No. 412,795, filed September 25, 1920, a machine switching system is disclosed wherein a toll operator is enabled to carry out the necessary coin collect and refund operations on 10 toll connections. In that application the toll operator is provided with two jacks, one a collect jack, and one a refund jack and an auxiliary cord circuit. By inserting the 15 plug of the cord into one or the other of the jacks depending on which of the collect or refund operations is to be carried out, and then operating a dial individual to the cord circuit, a coin control switch automatically engages the trunk employed in establishing 20 the toll connection, and sends over the connection current, characteristic of the jack employed, to effect the operation of the coin box mechanism at the subscriber's station.

It is an object of this invention to improve the system disclosed in the aforementioned copending application for effecting coin collect and refund operations.

This object is accomplished by providing a system wherein one jack is employed 30 in connection with a pair of manually operable keys for accomplishing the collect and refund operation of the coin box mechanism, one key being actuated to effect the collection of coins and the other key to effect the 35 refund of coins. Actuation of one key initiates the application of the refund and actuation of the other key initiates the application of the collect current. The selected 40 current is then held connected to the called line independently of the depressed key until the coin in the coin box is disposed of.

The invention will be readily understood from the following detailed description made with reference to the accompanying 45 drawing in which a toll train, shown schematically, is adapted to connect a toll operator's position at D with a subscriber's line of the coin box type represented at A. The schematic representation of the toll train 50 shows a toll operator's cord B, a plurality of automatic selectors C and E, and the connector F. A complete description of the operation of the equipment shown schematically in the drawing may be had by referring to the above mentioned copending ap-

plication, and as this equipment does not enter into the present invention, no detailed description thereof will be entered into in this application. Below the train of automatic switches is shown the circuit details 60 of a coin control switch terminating in a plurality of multiple jacks. To the extreme left an operator's cord circuit and dialing equipment are shown, by virtue of which the coin control switch is caused to automatically engage a trunk line and control the operation of the coin box mechanism at a distant subscriber's station.

It will be assumed that the toll operator 70 has established the desired connection over the selectors C and E and connector F and has requested the subscriber at A to deposit the required amount in coins in the coin receptacle located at station A.

Assuming that the coins have been deposited by the subscriber at A and the operator at D, having received the tone signals 75 verifying the amount deposited, desires to collect the same, she picks up the plug 10 and inserts it into jack 11 after noting 80 whether the busy signal 14 is operated or not. The insertion of plug 10 into jack 11 closes a circuit for relays 12 and 13, which may be traced from grounded battery, 85 through the winding of relay 12, sleeve contacts of plug 10 and jack 11, to ground, through the winding of relay 13. Relay 13 operates in this circuit and in attracting its right hand armature effects the actuation of the drop signals 14 and 15 located at the 90 positions at which multiples of jack 11, appear, to notify the operators thereat that the coin control switch designated by these drops has been taken for use.

Relay 12 also operates and disconnects, at 95 its left hand armature and back contact, the busy test circuit, and at its right hand armature establishes a circuit for slow-to-release relay 16 which circuit includes the normal contacts of key 17. Relay 16 operates and 100 establishes a circuit for the pulsing relay 20 which may be traced from grounded battery 21, left hand armature and back contact of relay 22, front contact and left hand armature of relay 12, tip contacts of plug 10 and jack 11, conductor 23, winding of relay 20, conductors 46 and 24, outermost right hand armature and back contact of relay 25, outer 105 right hand armature and back contact of relay 26, outer right hand armature and 110

back contact of relay 27, conductor 28, ring contacts of jack 11 and plug 10, ring conductor 29 of the cord, normal lower contacts of the dial 30, back contact and right hand armature of relay 22, front contact and armature of relay 16, normal contacts of key 17 to ground over the right hand armature and front contact of relay 12. Relay 20 operating in this circuit establishes an obvious circuit for relay 31 the purpose of which will hereinafter appear.

The operator knowing the number of the trunk G employed in establishing the connection to the subscriber's line A rotates the dial 30 to send out impulses corresponding to the number of this trunk in order to place the coin control switch in operative relation therewith. The apparatus shown at the right of the broken line in the drawing is located at the distant automatic office, that is to say, in the same office as the selector C. The equipment at the left of the broken line is located at the toll office.

Upon the return movement of the dial 30 impulses are transmitted to the impulse relay 20 over the circuit hereinbefore traced. Upon each retraction of the armature of this relay an impulse is transmitted over the following circuit to the vertical magnet of the switch: from ground, armature and back contact of relay 20, inner armature and front contact of relay 31, normally closed contacts of off-normal switch 33, winding of slow-to-release relay 34, to grounded battery, through the winding of vertical magnet 32. As relay 20 follows the interruptions at the dial contacts, the vertical magnet 32 operates in series with relay 34 and raises the switch shaft and its associated wipers to the desired level in the well known manner. Relay 34 being slow-to-release does not follow the interruption but remains energized between pulses.

Upon the first vertical step of the switch shaft the off-normal switch 33 operates, so that the succeeding pulses pass by way of the contact 35 and the armature and front contact of relay 34. Upon the cessation of the impulses slow relay 34 releases and prepares a circuit for the rotary magnet 36. When the dial is again actuated to send out the next series of impulses, the pulses traverse a path extending from ground, armature and back contact of relay 20, inner right hand armature and front contact of relay 31, contact 35 of off-normal switch 33, armature and back contact of relay 34, conductor 38, winding of slow release relay 37, contacts 39 of off-normal switch 40, to grounded battery, through the winding of rotary magnet 36. Rotary magnet 36 in following the impulses, moves the shaft and wipers around into engagement with the trunk terminals 41 and 42. Relay 37 operates in series with the magnet 36 but being slow-to-release does

not follow the impulses. In operating on the first impulse, relay 37 substitutes its inner armature and front contact for the lower contacts of off-normal switch 40 so that when switch 40 operates on the first rotary step of 70 the switch shaft the pulsing circuit is maintained intact.

After the last impulse of this series, relay 37 drops back and closes the following circuit for relay 27. Grounded battery, 75 winding of magnet 36, upper contacts of off-normal switch 40, back contact and outer armature of relay 37, conductor 43, innermost left hand armature and back contact of relay 25, to ground through the right 80 hand winding of relay 27. Relay 27 operates in this circuit but magnet 36 remains inert, since it is marginal. In attracting its outer right hand armature, relay 27 removes the normally existing short circuit from the 85 lower winding of relay 44 and the winding of relay 45. This circuit may be traced from the right hand lower winding terminal of relay 44, winding of relay 45, conductors 46 and 24, outermost right hand armature 90 and back contact of relay 25, outer right hand armature and back contact of relay 26, outer right hand armature and back contact of relay 27, conductor 28, to the left hand lower winding terminal of relay 44. The removal of this short circuit causes relay 45 to energize in series with relays 20 and 44 over the tip and ring contacts of jack 11 and plug 12 to battery and ground in the cord circuit. Relay 44 does not operate at this time 100 since the direction of the flow of current therethrough is not in the proper direction. In attracting its outer left hand armature, relay 27 also establishes a circuit for the upper winding of relay 44 which may be 105 traced, from grounded battery, upper winding of relay 44, resistance element 61, conductor 50, outer left hand armature and front contact of relay 27, conductors 51 and 52, to ground over the outer armature and front contact of relay 31. Relay 44 is so wound that when both of its windings are energized in opposite directions it does not operate, as in the case just described. Relay 27 in attracting its inner left hand armature 110 prepares an energizing circuit for its own left hand winding and in attracting its inner right hand armature prepares an energizing circuit for relay 26.

Assuming now that the operator desires 115 to collect the coins deposited by the subscriber she actuates key 60 thereby establishing an obvious circuit for relay 22. Relay 22 thereupon operates and transposes the tip and ring conductors on the cord thereby 120 causing a reversal of current in the lower winding of relay 44.

The currents in the windings of relay 44 are now in such directions as to aid each other and relay 44 accordingly operates, and 125

- in attracting its lower armature short-circuits resistance 61 in series with the upper winding of relay 44 thereby increasing the pull exerted on the armatures of this relay.
- 6 In attracting its inner lower armature relay 44 short circuits relay 20 whereupon it releases. Relay 44 in operating locks under control of relays 25, 27 and 31 and independently of key 60, so that as soon as the operator depresses the key 60 it may be released and the consequent reversal of battery flow over the line will not release relay 44. Relay 20 in retracting its armature opens the circuit for slow relay 31, which, 15 however, is still held operated from ground on the armature of relay 45. A circuit for relay 26 may now be traced from grounded battery, right hand winding of relay 26, normally made contacts of relay 26, left hand winding of relay 26, inner right hand armature and front contact of relay 27, front contact and inner armature of relay 31, to ground, over the back contact and armature of relay 20. Relay 26, in attracting 20 its outer right hand armature, opens at another point the short circuit normally existing about the winding of relay 45 and the lower winding of relay 44. In attracting its inner right hand armature relay 26 locks itself to ground at the outer armature of relay 31 by way of the left hand armature and back contact of relay 71. In attracting 25 its inner left hand armature relay 26 completes a holding circuit for the left hand winding of relay 27 over conductor 86 to ground at interrupter 85. In attracting its outer left hand armature a circuit is established for the left hand winding of relay 25 which may be traced from grounded battery, left hand winding of relay 25, outer left hand armature and front contact of relay 26, conductor 51, to ground over the outer armature and front contact of relay 31.
- Relay 25 in operating in the circuit previously traced, establishes a locking circuit for itself which may be traced from grounded battery, right hand winding of relay 25, front contact and innermost right hand armature of relay 25, conductor 72, front contact and inner armature of relay 31, to ground at the armature and back contact of relay 20. The purpose of the aforementioned locking circuit for relay 25 is to insure the operation of this relay during the period of collecting the coins at the paystation regardless of whether the operator has restored her collect coin key to normal or not. In other words relay 25 is under the joint control of the operator's coin key and the coins in the coin-box. In attracting its innermost left hand armature relay 25 opens the circuit for the right hand winding of relay 27. The operation of the outermost right hand armature of this relay performs 55 a similar function as does the outer right

hand armature of relay 26 as hereinbefore stated. A guard circuit for the upper winding of relay 44 is effected by the actuation of the middle left hand armature of relay 25. This circuit may be traced from grounded 70 battery, upper winding of relay 44, front contact and lower armature of relay 44, conductors 50 and 73, front contact and middle left hand armature of relay 25, to ground over the outer armature and front contact of relay 31. In attracting its outermost left hand armature, relay 25 connects the collect tone signal source 74 to the operator's headset (not shown) over the wiper 42, and its associated brush in order to give the operator an audible signal during the collection of coins at the paystation. The condenser 75 in the tone circuit prevents any direct current from the tone apparatus from interfering with the talking circuit of the 80 established connection. When relay 25 operated as hereinbefore described, the circuit for the right hand winding of relay 27 is opened at the innermost left hand armature and back contact of relay 25 and should lead 85 be associated with an insulating segment of the interrupter 85 relay 27 restores. Relay 27 in restoring opens its locking circuit and establishes a circuit for relay 71 over the inner left hand armature and front contact 90 of relay 26, to ground at the interrupter 85. It will be noted that should relay 25 operate at a time when the brush of interrupter 85 is on an insulating segment relay 27 will 100 restore since the circuit for its left hand winding will also be opened. If, however, relay 25 should open the right hand circuit of relay 27 when the brush is on a metallic segment, relay 27 will remain locked up to ground at the interrupter 85 and will remain 105 so operated until the brush makes contact with the next insulating segment of the interrupter. Relay 27 is locked up to the ground on interrupter 85 in order to prevent it restoring during the period when the interrupter ground lead 86 is grounded and consequently causing the energization of relay 71 for only part of the time during which the lead 86 is grounded. Relay 71 must be operated during the entire period 110 of the grounding of lead 86 so that current of positive polarity from battery 80 will be on the line for a sufficient length of time to insure the proper functioning of the apparatus at the paystation. 115

Relay 71 operates and at its left hand armature and back contact opens the locking circuit for relay 26, and in attracting its right hand armature places the positive polarity of battery 80 on the contact 42 of the trunk multiple by way of the winding of relay 81. A path now exists which may be traced from the positive pole of grounded battery 80, front contact and inner upper armature of relay 44, winding of relay 81, 125 130

front contact and right hand armature of relay 71, switch contacts 42, brush 99, terminal 98, winding of relay 97, contacts 92 of relay 93 to ground. Relay 97 operates and connects relay 93 to the interrupter 94 whereupon the coin box mechanism at station A is operated as completely described in the aforementioned copending application. Relay 81 operates in series with the coin collect and refund apparatus at station A and closes the locking circuit for slow relay 26 which was opened when relay 71 operated. Relay 26, being slow-to-release, however, did not restore during the period existing between the operations of relays 71 and 81. When the ground is removed from the interrupter lead 86, relay 71 restores removing the positive polarity of battery 80 from the line and opening the circuit for relay 81.

If, on the first application of ground to the lead 86 by the interrupter 85, the coin box mechanism did not dispose of the coin, relay 71 on operating when the interrupter ground lead 86 is again grounded performs the functions as previously described. This cycle of operation will be repeated until the coin collect and refund apparatus at station A has disposed of the coin.

When the coin collect and refund apparatus at station A has disposed of the coins, relay 71 on operating when the interrupter ground lead 86 is again grounded opens the locking circuit for relay 26 and associates battery 80 with the contact 42, through the winding of relay 81. Since the coins have been disposed of at the paystation A the circuit for the coin collect and refund apparatus is opened at the coin contacts 96 and the circuit for relay 81 will therefore be opened. Relay 26 restores when its circuit is opened by the operation of relay 71 the circuit of relay 81 being opened at the coin contacts 96. The restoration of relay 26 does not deenergize relay 25 since this relay remains locked from ground at relay 20, over conductor 72 and its own innermost right hand armature and front contact. Relay 26 in restoring, however, opens at its inner left hand armature and front contact, the circuit for relay 71 which thereupon releases and removes battery from the switch contact 42.

The operator holds key 60 operated until she can recognize the tone signal on the line thereby checking the operation of the coin collect switch. Upon receiving this tone, the operator restores her key 60 to normal thereby opening the circuit for relay 22 which restores and reverses the current in the line. Relay 20 will thereupon operate and relay 45 will release due to the reversal of battery in the line circuit. Relay 20 in attracting its armature opens the locking circuit for relay 25 and closes

through a holding ground for relay 31. Relay 25 restores and in retracting its outermost left hand armature removes the collect tone from the line. At its middle left hand armature relay 25 opens up the circuit including the upper winding of relay 44 which relay thereupon restores. At its innermost left hand armature relay 25 establishes an energizing circuit for relay 27 which performs no function at this time since the circuit for relay 71 has already been opened at the inner left hand armature and front contact of relay 26.

It is apparent now that with the same setting of the coin control switch, the operator can again effect the operation of the coin box mechanism in whatever manner she desires either to collect or refund coins.

Should the operator desire to refund the coins instead of collect them as hereinbefore described she will operate the refund key 17 thereby deenergizing slow-to-release relay 16. Due to relay 16 being slow-to-release the circuit for relays 20 and 45 is momentarily opened causing them to release. The operation of marginal relay 20 when the normal contacts of relay 16 are closed is prevented by the inclusion of resistance 70 in its circuit. Relay 45 being sensitive operates however. Relay 20 having been energized upon insertion of plug 10 into jack 11 as hereinbefore described. Since key 60 is in its normal position, relay 22 will not energize thereby preventing the reversal of current through the lower winding of relay 44. Relay 44 accordingly remains inert so that negative current from battery 90 will be sent over the established connection to the coin box station by way of the armature and front contact of relay 71 which will have operated in the same manner as described in connection with the collect operation. The coin box mechanism will then function to refund the coins. At its uppermost armature and back contact relay 44 connects the source 91 of tone current to the wiper 41 to notify the operator that the switch has operated to refund the coins. After receiving the tone the operator restores key 17 to normal whereupon relay 20 operates. The operation of the remaining apparatus is the same as described in the previous description and need not be repeated.

When the coins have been properly disposed of, the operator removes plug 10 from jack 11 whereupon relays 20 and 45 restore causing the release of relay 31. A circuit now exists which may be traced from grounded battery through the winding of release magnet 92, upper contacts of off-normal switch 33, back contact and inner armature of relay 31, to ground over the back contact and armature of relay 20. The release magnet 92 operates and releases the coin control switch. As the switch shaft restores to normal the upper

6 contacts of off-normal switch 40 are opened
7 thereby opening the circuit for the right
8 hand winding of relay 27 allowing this relay
9 to restore. As soon as the shaft restores to
10 normal the circuit for release magnet 92 is
11 opened at the upper contacts of the off-
12 normal switch 33.

What is claimed is:

1. In a telephone system, the combination
10 with a telephone line, a connection comprising
11 a connecting circuit, said line and automatic
12 switches, of a coin box at the substation
13 of said line having a coin disposal magnet,
14 an operator's position, an automatic
15 switch at said position and controlled there-
16 from to connect with said connecting circuit,
17 an electrical path to said automatic switch
18 over which it may be set, and means for se-
19 lectively operating said magnet over said
20 path.

2. In a telephone system, the combination
with a telephone line, a connection comprising
a connecting circuit, said line and automatic
switches, of a coin box at the substation
of said line having a coin disposal magnet,
an operator's position, an automatic
switch at said position and controlled there-
from to connect with said connecting circuit,
a source of refund current, a source of col-
lect current, an electrical path to said auto-
matic switch over which it may be set, and
means effective over said path for selecting
one of said current sources to correspond-
ingly operate said magnet when the connect-
ing circuit is selected.

3. In a telephone system, the combination
with a telephone line, a connection comprising
a connecting circuit, said line and automatic
switches, of a coin box at the substa-
tion of said line having a coin disposal mag-
net, an operator's position, an automatic
switch at said position and controlled there-
from to connect with said connecting circuit,
a jack in which the circuit leading to said
automatic switch terminates, a source of re-
fund current and a source of collect current,
a dial, a plug adapted to be inserted in said
jack to associate said dial with said switch
to set the same on said connecting circuit,
and means effective subsequent to the inser-
tion of said plug in said jack for selectively
associating either of said current sources
with said connecting circuit to correspond-
ingly operate said magnet.

4. In a telephone system, the combination
with a telephone line, a connection comprising
a connecting circuit, said line and automatic
switches, of a coin box at the substa-
tion of said line having a coin disposal mag-
net, an operator's position, an automatic
switch at said position and controlled there-
from to connect with said connecting circuit,
a jack in which the circuit leading to said
automatic switch terminates, a source of re-
fund current and a source of collect current,

a dial, a plug adapted to be inserted in said
jack to associate said dial with said switch
to set the same on said connecting circuit,
and manually operable means effective sub-
sequent to the insertion of said plug in said
jack for selectively associating either of said
current sources with said connecting circuit
to correspondingly operate said magnet. 70

5. In a telephone system, the combination
with a telephone line, a connection comprising
a connecting circuit, said line and automatic
switches, of a coin box at the substation
of said line having a coin disposal magnet,
an operator's position, an automatic
switch at said position and controlled there-
from to connect with said connecting circuit,
a jack in which the circuit leading to said
automatic switch terminates, a source of re-
fund current and a source of collect current,
a dial, a plug adapted to be inserted in said
jack to associate said dial with said switch
to set the same on said connecting circuit, a
collect key, a refund key, and means respon-
sive to the actuation of either of said keys to
associate a corresponding source of current
with the connecting circuit whereby said
magnet is operated in a corresponding man-
ner. 80

6. In a telephone system, the combination
with a telephone line, a connection comprising
a connecting circuit said line and auto-
matic switches, of a coin box at the substa-
tion of said line having a coin disposal mag-
net, an operator's position, an operator's
headset thereat, an automatic switch at said
position and controlled therefrom to select
said connecting circuit, an electrical path
connected to said automatic switch over
which it may be set, a source of refund cur-
rent, a source of collect current, means for
selectively associating said current sources
with the connecting circuit to operate said
magnet in a corresponding manner, and two
sources of tone current adapted to be indi-
vidually associated with said headset in ac-
cordance with character of the current as-
sociated with the connecting circuit to oper-
ate said magnet. 100

7. In a telephone system, the combination
with a telephone line, a connection comprising
a connecting circuit said line and auto-
matic switches, of a coin box at the substa-
tion of said line having a coin disposal mag-
net, an operator's position, an operator's
headset thereat, an automatic switch at said
position and controlled therefrom to select
said connecting circuit, an electrical path
connected to said automatic switch over
which it may be set, a source of refund cur-
rent, a source of collect current, means for
selectively associating said current sources
with the connecting circuit to operate said
magnet in a corresponding manner, two
sources of tone current adapted to be indi-
vidually associated with said headset in ac- 110

115

120

125

130

cordance with the character of the current associated with the connecting circuit to operate said magnet, and means effective incident to the operation of said magnet in removing the tone current.

8. In a telephone system, the combination with a telephone line, a connection comprising a connecting circuit said line and automatic switches, of a coin box at the substation of said line having a coin disposal magnet, an operator's position, an operator's headset thereat, an automatic switch at said position and controlled therefrom to connect with said connecting circuit, a jack 10 in which the circuit leading to said automatic switch terminates, a source of refund current, a source of collect current, a dial, a plug adapted to be inserted in said jack to associate said dial with said switch to set 15 the same on said connecting circuit, means effective upon the insertion of said plug into said jack for selectively associating said current sources with said connecting circuit to correspondingly operate said magnet, two 20 sources of tone current adapted to be individually associated with said headset in accordance with the character of the current associated with the connecting circuit, means effective incident to the operation of 25 said magnet in removing the tone current, and means actuated upon the removal of said plug from said jack for restoring said switch.

9. In a telephone system, the combination 30 with a telephone line, a connection comprising a plurality of serially connected automatic switches and a subscriber's line, a coin box mechanism associated with said line, a coin control switch terminating in a jack 35 at an operator's position, a dial, a plug adapted to be inserted in said jack to connect said dial thereto whereby said switch is associated with the serially connected automatic switches, a relay associated with said 40 switch adapted to be energized in such a manner as to remain inert when said plug is associated with said jack, sources of currents of different characteristics, a second relay, and a key effective in operating said 45 second relay to reverse the current in said first relay and cause it to actuate whereby a certain one of said current sources is connected to said serially connected switches to 50 operate said coin box mechanism in a predetermined manner.

10. In a telephone system, the combination 55 with telephone lines, a connection comprising a connecting circuit, a pair of said lines and automatic switches, of a coin box

at the substation of one of said lines having 60 a coin disposal magnet, an operator's position, an automatic switch at said position and controlled therefrom to connect with said connecting circuit, a two-conductor circuit extending to said switch over which 65 it may be set, a pair of keys, a source of refund and a source of collect current, means controlled by said keys for selectively applying said refund and said collect current to said coin box, and means for automatically 70 continuing the application of the selected current to the coin box until the coin is disposed of.

11. In a telephone system, the combination 75 with telephone lines, a connection comprising a connecting circuit, a pair of lines and automatic switches, of a coin box at the substation of one of said lines having a coin disposal magnet, an operator's position, an automatic switch at said position and controlled therefrom to connect with said connecting circuit, a jack in which the circuit leading to said automatic switch terminates, a source of refund and a source of collect 80 current, a dial, a plug adapted when inserted in said jack to associate said dial with said switch to enable the operator to set the same switch on said connecting circuit, a key for each source of current, and means controlled by said keys for selectively impressing current from the corresponding source to cause said coin disposal magnet to collect or refund the coins.

12. In a telephone system, the combination 95 with telephone lines, a connection comprising a connecting circuit, a pair of said lines and automatic switches, of a coin box at the substation of one of said lines having a coin disposal magnet, an operator's position, an automatic switch at said position and controlled therefrom to select said connecting circuit, a two-conductor circuit extending to said switch over which it may be set, a source of refund and a source of collect 100 current, a pair of keys for selectively applying said sources of refund and collect current to the coin box, two sources of tone current the corresponding one of which is connected to said connecting circuit when current is applied to the line to operate said coin disposal magnet, and means for maintaining the tone source connected to the connecting circuit until the coin is disposed of and the selected key is restored to normal.

In witness whereof, I hereunto subscribe my name this 31st day of May A. D., 1923.

RAY L. STOKELY.
